FEED MECHANISM FOR INTERNAL
GRINDING MACHINES

Robert S. Hahn, Northboro, Mass., assignor to
The Heald Machine Company, Worcester, Mass.,
a corporation of Massachusetts

Application February 20, 1952, Serial No. 272,570

10 Claims. (Cl. 51—165)

1

This invention relates to feed mechanisms for internal grinding machines, particularly those in which the position of a cross slide determines the size of the work.

It has been the usual practice to arrange such machines so that in bringing the work and wheel together, the cross feed mechanism causes the wheel rapidly to approach the surface to be ground, and at a predetermined point to slow down and feed at an intermediate rate known as the rough grinding feed rate. The bulk of the material is removed during this rough grinding period. Commonly, rough grinding continues until the cross slide reaches a contact which causes separation of the wheel and work for truing.

Grinding is then resumed at a slower feed rate of the cross slide, which is termed the finish grinding feed rate, until the cross slide reaches a second contact which terminates the grinding cycle. At this point the workpiece is presumed to be ground to the proper size.

Quite accurate sizing might be obtained if the active surface of the wheel could be kept in an invariant position relative to the cross slide.

In practice it is found, however, that some fluctuations in workpiece size occur, especially if an attempt is made to increase the grinding rates. These size fluctuations are undesirable in many industries where it is desired to grind quickly large quantities of parts, all to exactly the same size.

These fluctuations in size which become pronounced at high grinding rates are due to variations in the amount of original stock to be ground out of each successive workpiece, to inherent variations in the rate of cutting exhibited by the wheel, and also to variations in the hardness of each successive workpiece. The force between wheel and work causes lateral and angular deflection of the parts, especially the wheel spindle which may be comparatively flexible, and the variations mentioned cause changes in these deflections. Hence the position of the wheel changes relative to the cross slide causing size variations.

Accordingly, this invention provides means for feeding the wheel against the workpiece in such a manner that the size fluctuations caused by varying deflections in the machine are reduced to a very low magnitude even under relatively high rates of grinding. The force-velocity characteristics of the cross slide feed are manipulated in such a way as to accomplish the desired results.

2

In previous machines of this general type the cross feed rate is essentially independent of the force acting between the wheel and work, i. e., a constant feed rate is established. This is highly desirable in order to round up and generally true the bore of the workpiece, but it is very undesirable for the purpose of controlling size, since the grinding force may fluctuate considerably as the wheel is fed into the workpiece and thereby cause variable deflections of the machine and consequently size variations.

I have found it desirable to control the cross slide so as to maintain between wheel and work a constant force which is essentially independent of feed velocity. Under some conditions of grinding, I may use a predetermined constant force for the rounding up or roughing part of the operation and a lower predetermined constant force for finishing to size. I may also find it preferable to use the constant rate type of feed for roughing and the constant force type for finishing. My invention is adapted to use either combination. By using a predetermined force independent of feed rate, the deflections in the machine may be kept uniform from piece to piece, the active surface of the wheel is in a definite position relative to the cross slide, close size control may be attained even at high grinding rates, and the angular position of the wheel support may be so fixed as to compensate for deflections and bring the active surface of the wheel parallel to the finished work surface.

I find it desirable, during the rounding up part of the operation, to hold one of the supports in such an angular relation to the path of reciprocation as to compensate for angular deflection in the supports.

In another embodiment of my invention I arrange the cross feed mechanism to apply to the cross slide a force which increases rapidly with any tendency for the slide to move in the direction to separate the wheel and work, but which is essentially independent of velocity in the feeding direction.

In the drawings:
Fig. 1 is a front elevation of a machine which embodies the invention.

Fig. 2 is a plan view of the portion of a machine of the invention including a wiring and fluid pressure diagram.

Fig. 3 is a view of switches and operating mechanism in one operative position.

Fig. 4 is a view similar to Fig. 3 with the switches in another position.

55. In the drawings, Figs. 1 and 2, grinding tool 1 is

shown mounted on a spindle 2 which is supported and driven by suitable power means such as a motor in a wheel head 3. The wheel head is adjustably fastened to a swivel plate 5 by gib 7 and 8 and the swivel plate 5 is pivoted at 10 to a slide 12. The gib 7 and 8 permit the wheel head 3 to be adjusted toward or away from its pivot 10 for a purpose to be described. The wheel head 3 may swivel horizontally around the pivot 10 on the slide 12 within limits determined in a clockwise direction by an adjusting screw 131, threaded in an extension 14 of the slide 12 and in a counter-clockwise direction by a similar screw 136 threaded in a slide extension 16. A slidable plug 18 loaded with a spring 139 in the slide extension 16 urges the wheel head in a clockwise direction against the screw 131 and a piston 29 in the slide extension 14 is arranged to urge the wheel head in a counterclockwise direction against the screw 136 and plug 18 when fluid under pressure is introduced to its cylinder 135.

The slide 12 moves in ways 13 on a base 17 in a direction (upwardly in Fig. 2) to allow cross feed motion to be imparted to the wheel relative to the work. A nut 22 attached under the slide 12 is engaged by a lead screw 125 in the base 17 and rotation of the lead screw 125 by an electric motor 123 through a pinion 126 and gear 127 advances and retracts the wheel head and wheel.

The workpiece 44 is held in a chuck 100 on a spindle 101 journaled in a work head 43 and driven by any convenient means, not shown. The workhead 43 is mounted on a slidable traverse table 42 arranged to be moved right and left as viewed to cause the wheel 1 to enter the work 44 in the usual manner so that it can then be fed against the work surface by the mechanism of the present invention. The workpiece 44 is traversed toward and away from the wheel 1 by suitable means such as fluid pressure from a pump 45, line 53 and reversing valve 46 acting in a cylinder 47 variously on either side of a piston 48 connected to the traverse table 42 through a piston rod 49, the fluid on the opposite side of the piston 48 exhausting through the valve 46 and a line 50 to a sump 52.

Fig. 2 shows the parts in rough grinding position with the wheel head 3 swivelled clockwise about the pivot 10 under force of the spring 130, so as to compensate for angular deflections in the wheel spindle and other parts due to the force between wheel and work and thereby to present the cutting surface of the wheel parallel to the desired grinding line. Adjustment of the desired amount of swivelling is obtained by the setting of the screw 131 in this position.

Means are provided for controlling and limiting to a predetermined value the amount of normal force exerted by the wheel against the work during grinding and, according to this invention, this is accomplished by measuring a deflection caused by the force and using this measure to control the feeding of the wheel against the work so as to maintain the predetermined force on the wheel.

The measuring is accomplished by a gage and the gage used to measure deflection may be of the non-contacting type, in which case it is convenient to measure the deflection of a rotating part such as the wheel spindle, work spindle or parts carried thereby.

One type of non-contacting gage is the air gage. Another type is the variable reluctance magnetic gage, a pair of which are shown in Fig. 2 and designated 102 and 103. These gages, which include coils 106 and 107, are mounted

close to the cylindrical periphery of the chuck 100 with air gaps 104 and 105 between the chuck and the gages. The coil 106 and a rheostat 108 in series with it form one leg of a conventional bridge circuit indicated at 70. The coil 107 and a rheostat 109 in series with it form another leg. The other two legs are impedances 110 and 111.

The bridge circuit 70 is supplied with alternating current from a power source 89 through a transformer 112. The output of the bridge is connected to an amplifier 113 through a wire 114, the upper leg of switch 142, contacts 115 and 116 of a switch 90, and also through a wire 117, the lower leg of switch 142, contacts 118 and 119 of a switch 137, a wire 117a and contacts 120 and 121 of switches 156 and 145 and a wire 145a.

The output from the amplifier 113 is fed to a standard electronic motor controller 122. The controller 122 is connected to the armature and field of the D. C. feed motor 123, by wires 210, 211, 212 and 213, the latter two being connected through a reversing switch 124.

The bridge circuit 70 is initially unbalanced so that when there is no deflection of the chuck 100 and its spindle 101 the output of the bridge is high and the wheel 1 is fed rapidly toward the work 44. After the wheel and work are in contact, the deflection of the chuck 100 caused by the force between wheel and work reduces the air gap 104 and increases the air gap 105, changing the reluctance of the gages 102 and 103, which tends to balance the bridge circuit 70, reducing its output to the amplifier 113 and reducing the speed of feed motor 123. The deflection caused by the force between wheel and work is thus held to a preset value during the roughing operation.

If it is desired to employ a constant rate instead of a constant force for the roughing operation, the switch 142 may be moved by hand or other means into its upper position, connecting the amplifier 113 through the contacts 116 and 115 to one side of the power source 82, and through the line 145a, the contacts 121, 120, the wire 117a and contacts 119 and 118 to a potentiometer 147 across the line 82. Roughing feed will then be at a fixed rate substantially independent of the force between wheel and work, instead of at a constant force, and as determined by the setting of the potentiometer 147.

At the conclusion of the roughing operation a switch 132 is closed by any conventional means, controlled, for example, as by a gage entering the work or as in Fig. 2, by the slide 12 reaching a preset position. An adjusting screw 37 on an extension of the slide 12 is preset to allow the switch 132 to close at the desired point. Closure of the switch 132 energizes a solenoid 133 from a power source 81 lifting a valve 134, which disconnects the cylinder 135 from an exhaust line 59 and connects it to a pressure line 53 from the fluid pressure pump 45, swivelling the head 2 counterclockwise against the pressure of the spring 130 to a locked position determined by the setting of the adjusting screw 136, ready for truing and finishing.

Lifting of the valve 134 also lifts a switch member 137 to which it is connected, connecting lines 138 and 139 to the contact 118a and the line 117 which short-circuits the rheostats 108 and 109. Lifting of the switch 137 also connects the amplifier contact 116a to a contact 141, connects contacts 140 and 143 and disconnects the contacts 118 and 119, which interrupts the input to the amplifier 113 and stops the feed for truing.

As the table 42 is moved to the left to separate the wheel and work axially in the conventional

manner for truing, a table dog 144 moves the switch 145 counterclockwise to disconnect the amplifier circuit through the wire 145a temporarily and a swinging dog 155 moves the switch 156 clockwise, as shown in Fig. 3.

As the table returns to grinding position, the dog 144 restores the switch 145 to clockwise position, completing a connection from the bridge circuit 70 to the amplifier 113 through the line 117 across the contacts 140, 143, through a wire 143a and across the contacts 146 and 121 and the wire 145a. This starts the finishing feed, but as the rheostats 106 and 109 are now short-circuited, a relatively small deflection is sufficient to slow down the feed motor 123. Consequently the force applied to the wheel while finish grinding may be relatively light.

When the conclusion of the finishing operation is signalled in the usual way, either by the entry of a gage or, as shown, by the movement of the slide 12 to a preset position, the table 42 is moved to its extreme left, or loading position. As grinding is finished a switch 148 is allowed to close by the movement of an adjusting screw 38 to energize a solenoid 149 from the power source 81 which closes a switch 150 and establishes a holding circuit through a switch 151, and also lifting the switch 124 and reversing the feed motor 123, retracting the slide 12 until it opens the switch 151, allowing the switch 124 to drop into the feeding position shown. Retraction of the slide 12 again opens the switch 132, allowing the switch 137 to drop into rough feed position, as shown, and the valve 134 to drop into its lower position, connecting the cylinder 135 to exhaust and allowing the spring 130 to swivel the head 2 back into roughing position against the screw 131.

Movement of the table 42 further out to the loading position moves the switch 145 to its counterclockwise or "off" position, and the switch 156 to its counterclockwise, or "roughing" position (Fig. 4). When the table is next moved into grinding position, the dog 155 rides over the switch 156, but the dog 144 moves the switch 145 to its clockwise position and feeding is resumed.

The wheel head 3 may be adjusted in the gibs 7 and 8 toward or away from its pivot 10 until the radial movement of the wheel 1, when the head 3 is swivelled from roughing to finishing position, approximately equals the deflection set up during the roughing operation. Then when the wheel and work are brought into overlapping relation after truing, only a minimum feeding motion is required to resume grinding. The screws 131 and 136 are adjusted to make the ground surface truly cylindrical, or with the desired taper, both at the end of the roughing and the end of the finishing operations.

I claim:

1. In an internal grinding machine, a work support, a wheel support having a grinding tool, said supports being relatively movable to feed the tool against a workpiece in said work support, feed means to feed said tool against the workpiece, gage means to measure the deflection in one of said supports resulting from the force between tool and work, and rate control means for said feed means responsive to said gage means whereby said deflection is maintained substantially constant during a part of the grinding operation.

2. In an internal grinding machine, a work support, a wheel support having a grinding tool, said supports being relatively movable to feed the tool against a workpiece in said work support, feed means to feed said tool against the work-

piece with a predetermined force substantially independent of the feed rate, and control means for said feed means, said control means being constantly responsive to a deflection of one of said supports resulting from the force between tool and work during grinding.

3. In the combination as set forth in claim 2, one of said supports being pivotally movable relative to the other and means automatically to change the pivotal relation of said supports at a predetermined point during grinding thereby compensating for deflections in said supports caused by the force between said grinding tool and work.

4. In the combination as set forth in claim 2, one of said supports being arranged for reciprocation relative to the other, a member controlling the angle between one of said supports and the path of said reciprocation, stops for said member, one of said stops having a fine adjustment, means to press said member against one of said stops, and means responsive to the position of one of said supports for pressing said member against another one of said stops thereby compensating for deflections in said supports caused by the force between said grinding tool and work.

5. In the combination as set forth in claim 2, said constant force feed means being operable during a part of said cycle, and means operating during another part of said cycle to feed said tool against the workpiece at a predetermined rate substantially independent of the force between said tool and said work.

6. In an internal grinding machine, a work support, a wheel support having a grinding tool, said supports being relatively movable to feed the tool against a workpiece in said work support, feed means including a motor to feed said wheel against the workpiece, a gage to measure deflections in one of said supports caused by the force between the tool and the workpiece and speed control mechanism for said motor, said speed control mechanism being responsive to said gage.

7. In combination as set forth in claim 6, means automatically to vary the response of said speed control means to said gage at a predetermined point whereby the feed rate changes for a given deflection in said support.

8. The method of grinding an internal surface of revolution in a workpiece, comprising the steps of rotating the workpiece in a support, rotating a grinding tool in a support, feeding one of said supports at a rate substantially independent of the force between tool and work for a rounding operation, then feeding one of said supports with a feed controlled by the deflection of one of said supports for a finishing operation thereby maintaining said deflection constant, and terminating the grinding when one of said supports reaches a predetermined position while said constant deflection is maintained.

9. The method of grinding an internal surface of revolution in a workpiece, comprising the steps of rotating the workpiece in a support, rotating a grinding tool in a support, feeding one of said supports at a rate substantially independent of the force between tool and work for a rounding operation, then feeding the tool into the work with a force substantially independent of the feed rate for a finishing operation thereby maintaining a constant force between said supports, and terminating the grinding when one of said supports reaches a predetermined position while said constant force is maintained.

10. In an internal grinding machine, a work support, a wheel support having a grinding tool, one of said supports being arranged to move in a path of reciprocation relative to the other to enter the wheel in the work and said supports being relatively movable to feed the tool against a workpiece in the work support, feed means to feed the tool against the workpiece with a pre-determined force substantially independent of the feed rate, gage means to measure the deflection in one of said supports resulting from the force between tool and work, rate control means for said feed means responsive to said gage means maintaining said deflection substantially constant during a part of the grinding operation, and means operating in response to said deflection to change the angular relation between one of the supports and said path of reciprocation thereby compensating for said deflection.
